Primary Examiner — Ricky Pham(74) *Attorney, Agent, or Firm* — Gallagher & Dawsey Co., LPA; David J. Dawsey; Michael J. Gallagher(57) **CLAIM**

The ornamental design for a portion of a base for a food slicer, as shown and described.

DESCRIPTION

FIG. 1 is a front perspective view of the design;
FIG. 2 is left side elevation view thereof;
FIG. 3 a right side elevation view thereof;
FIG. 4 is a front elevation view thereof;
FIG. 5 is a rear side elevation view thereof;
FIG. 6 is a top plan view thereof; and,
FIG. 7 is a bottom plan view thereof.
The broken lines show unclaimed subject matter only and
form no part of the claimed design.
